UNITED STATES PATENT OFFICE

EUGENE H. BIRD, OF PITTSBURGH, PENNSYLVANIA, ASSIGNOR TO THE KOPPERS COMPANY, OF PITTSBURGH, PENNSYLVANIA, A CORPORATION OF PENNSYLVANIA

REMOVAL OF NAPHTHALENE CONSTITUENTS FROM GASES

Application filed February 13, 1923. Serial No. 618,838.

This invention relates essentially to the removal of naphthalene and analogous hydrocarbons from coal gas, water gas, coke oven gas, or other gases employed for heating or illuminating purposes. The process is preferably applied after the gas has been subjected to the usual treatment of cooling and condensation and the removal of tar and ammonia. Although the invention is hereinafter described as applied to the removal of naphthalene, which is one of the most important applications of the invention, the invention is not limited in scope to this application, being of general utility for the removal from the gas of other hydrocarbons, such as are characterized by having a relatively small vapor tension and by being present in vapor form in gas at ordinary ranges of temperature, in relatively small amounts, and near their saturation limit. Anthracene is an example of such other high hydrocarbons, the removal of which may be effected by the present invention.

Naphthalene is formed in connection with the production of most types of fuel or illuminating gases. It is a solid at ordinary temperatures and pressures and has a melting point of approximately 80° C. It, however, exists in a state of vapor diffused through the gas at temperatures far below its melting point and of course has at each temperature a definite saturation limit. For example, 100 cu. ft. of dry gas saturated with naphthalene at 25° C. contain 25.5 grains of naphthalene. At 20° C. the same volume of saturated gas carries 15.5 grains, and at 15° C. the saturation limit is 9.4 grains of naphthalene. When gas saturated with naphthalene at any temperature below its melting point is cooled, the vapor passes directly into the solid state in the form of very light flaky flat crystals which occupy a large volume in proportion to their weight. This property renders the naphthalene extremely troublesome to the gas manufacturer and to the consumer. Although the weight of the naphthalene that may be actually deposited from a given quantity of gas may be small, the crystals occupy so large

a space as to obstruct the distributing mains and service apparatus.

Naphthalene which has once been deposited will pass from the solid state directly into that of vapor as soon as it is slightly warmed or brought into contact with a gas carrying less naphthalene than the saturation limit and thus naphthalene that has been deposited in the pipes in quantities too small to cause trouble may evaporate again and pass off with further amounts of gas when this reaches the deposit in an unsaturated condition. This same naphthalene may be redeposited farther along in the system if the gas becomes sufficiently cool and so serious local stoppages may occur although the system as a whole may contain very little naphthalene.

Under present conditions of gas manufacture, naphthalene troubles have become more numerous and more acute than formerly because in present practice the tendency is to produce what is technically known as a dry gas, i. e. a gas containing little or no readily condensable oils. If the gas contains a sufficient amount of such oils as it commonly did in former practice, these would condense along with the naphthalene and prevent the latter from going into the flaky crystalline condition. In fact the amount of oils so condensed would, in most cases, be sufficient to keep the naphthalene in solution so that it would eventually find its way to the drains and drips and be pumped out of the system. In present practice, however, the gas seldom contains sufficient oils to prevent naphthalene stoppages and trouble may occur even when the gas leaving the works contains as little as 5 or 6 grains of naphthalene per 100 cu. ft.

It is very desirable, therefore, to treat the gas at the point of manufacture in such a way that it will be practically free from naphthalene. A considerable amount of the naphthalene may be removed by thoroughly cooling the gas, by the aid of water either in indirect coolers or in scrubbing apparatus in which the water is brought directly into contact with the gas. However, the best that has been accomplished by the cooling proc-

ess is to remove such amounts of naphthalene as occur beyond the saturation limit determined by the temperature of the water, so that the gas after the cooling treatment in most cases still contains enough naphthalene to cause trouble.

Methods that have so far been attempted for the removal of the small amounts of naphthalene that remain, even after cooling

- 10 the gas as much as possible, have been based on the fact that naphthalene is soluble in oils, such as anthracene oil, creosote oil and various petroleum oils. Two principal difficulties have been encountered in this connection.
- 15 The first arises from the fact that very small amounts of naphthalene have to be dealt with and these small amounts are distributed through very large volumes of gas and there has heretofore been considerable difficulty in securing a distribution of the oil through the large gas volume adequate to reach the naphthalene effectively without using excessive quantities of oil. Creosote oil, for example, will readily take up 5% of 20 its weight in naphthalene. In ordinary cases, we have about 10 to 15 grains of naphthalene to be removed per 100 cu. ft. of gas so that in a plant producing 1,000,000 cu. ft. of gas per day from 40 to 60 gallons of oil per day should be sufficient for the removal of the naphthalene. Some gasworks have experimented with mechanical scrubbers for the application of oil to the gas, but these have the disadvantages of causing the 30 gas to lose its pressure, of mechanical troubles, and of requiring considerable attention with heavy labor expense. A second difficulty in connection with the present attempts to apply oil for naphthalene removal is that 35
- 40 if large amounts of oil are used, they absorb considerable amounts of benzols, thus lowering the heating value of the gas. In dealing with domestic gas in most cases under normal conditions the value of the benzols in the gas is greater than their value recovered from the oil.
- 45

This invention provides an effective process for bringing small amounts of oil in contact with large volumes of gas for the substantially complete removal of the naphthalene. By the invention, the absorption of benzol or other enriching hydrocarbon from the gas is eliminated, or reduced to such a mere trace as to be of no practical consequence whatever. Moreover, expensive installations are eliminated, there is practically no loss of gas pressure, and the apparatus is simple, inexpensive, and requires little if any attention.

- 50
- 55
- 60 In addition to the general objects recited above, the invention has for further objects such other improvements or advantages in operation and results as are found to obtain in the process or apparatus hereinafter described or claimed.

In the accompanying drawing forming a part of this specification and showing, for purposes of exemplification, a preferred form and manner in which the invention may be embodied and practiced, but without limiting the claimed invention to such illustrative instance, the figure shows a diagrammatic representation of apparatus for carrying out the process of the invention.

According to the invention, the gas is passed through a bed of absorbent solid material, such as wood shavings, coke breeze or other suitable material offering relatively large surfaces and capable of holding a considerable amount of liquid by adhesion. The naphthalene solvent, or carrier liquid may be pumped intermittently over this bed at such intervals and rates as to insure proper distribution throughout the bed, as to bring about an intimate contact between relatively large volumes of gas and the relatively small amount of liquid. Referring to the drawing, A represents a purifier box, for example, of the type commonly employed in the iron oxide process for removing hydrogen sulfide from gas. The box is filled with a bed B of absorbent solid material having characteristics mentioned above. A satisfactory material for this purpose is coke breeze. The bed of absorbent material is supported on the grid C located above the bottom of the purifier box. It is preferable to employ a relatively wide and shallow bed so that the pressure drop of the gas will be relatively small. The gas is passed from the inlet K continuously underneath the grid and rising through the bed, passes out of the top of the box, through the outlet L. The absorbent liquid, such as oil, is pumped from the tank D through pump E, and the line F, to the sprays G, where it is distributed over the bed. This pumping is conducted at such a rate as to insure adequate distribution of the oil through the bed. The amount of oil used depends upon the quality of the oil and the amount of naphthalene in the gas. Where employing a petroleum oil such as "gas oil," the amount of oil used is greater than with creosote or anthracene oil ordinarily employed, but there is an advantage in using the petroleum oil because of the comparative ease of distributing the relatively large amounts and because used oil need not be regenerated but may be disposed of by mixing it with the coal in the case of a coal gas plant or by using it in the carburetors in the case of a water gas plant. When using gas oil there may for example be employed 100 to 200 gallons for substantially complete removal of the naphthalene. This amount of oil will remove only insignificant amounts of benzol and the consequent reduction of heating value is less than 1 B. t. u. per cu. ft. of gas. The oil need be pumped only at comparatively long inter-

vals, e. g. once every eight hours; but the rate of pumping should be rapid so as to effect good distribution. The pumping may be started and stopped automatically by a clockwork arrangement operating in conjunction with the pump E. The used oil drains from the bottom of the box through the sealed pipe H, into the tank I, from which it may be disposed of as above described or it may be regenerated if desired by removing the naphthalene by heating, aeration or steaming, or by a combination of any of these methods.

The term "naphthalene constituents" employed in the claims is not limited to naphthalene, but includes analogous hydrocarbons for example, anthracene, having the naphthalene characteristics hereinbefore mentioned.

The invention as hereinabove set forth may be variously embodied within the scope of the claims hereinafter made.

I claim:

1. A continuous process for removing certain constituents from gases, which comprises: continuously passing the gas through a bed of solid material drenched with a liquid for removing said certain constituents from the gas; discharging spent liquid containing the said constituents from said bed during gas flow therethrough; and supplying said liquid to said bed during such continuous gas treatment by intermittently drenching the bed with the liquid at long intervals for a shorter period of time than such interval and at a high rate of speed, and so delivering at each of such intermittent drenchings substantially such volume of liquid as to effect distribution throughout the bed and bring about an intimate contact between relatively large volumes of gas and the relatively small amount of liquid.

2. A continuous process for removing naphthalene constituents from fuel gases, which comprises: continuously passing the gas through a bed of non-reacting solid material drenched with a naphthalene absorbent liquid; discharging absorbent liquid containing the naphthalene from the bed of non-reacting material during gas flow therethrough; and supplying the absorbent liquid to said bed during such continuous gas-treatment by intermittently drenching the bed with the liquid at long intervals for a shorter period of time and at a high rate of speed.

3. A method for distributing liquid over a bed of solid material for effecting contact of gas passing through said bed with liquid therein, which comprises: passing gas through a bed of solid material treated with a liquid for contact with the gas; discharging spent liquid from said material; and supplying said liquid to said bed by intermittently delivering at long intervals substantially the entire volume of liquid required to

be delivered for a next interval and at a high rate of speed and for a shorter period of time than such interval, each of such intermittent deliveries being substantially of such volume as to effect distribution throughout the bed and bring about an intimate contact between relatively large volumes of gas and the relatively small amount of liquid.

In testimony whereof I have hereunto set my hand.

EUGENE H. BIRD.
